[57] ABSTRACT

A tubular arrow shaft is sealed at its nocked end portion. The seal and a slidable piston in the shaft retain a compressible fluid therebetween. Forwardly of the piston, a plurality of projectiles are aligned axially in the shaft. The forward acceleration of the arrow by a bow and the inertia of the projectiles compresses the retained fluid while accelerating the projectiles up to the arrow velocity. Thereafter, the fluid expansion causes substantially all the energy of the arrow to be transferred to the projectiles which are propelled toward a target while the arrow falls to the ground within a few feet of the bow.

FIG. 5.

1
SHOT PROPELLED ARROW

This invention relates to arrows and more particularly to an arrow for propelling a plurality of projectiles to a target.

With a recent expanded interest in archery, increasing numbers of sportsmen have been turning to the bow and arrow for shooting both targets and game. This interest has been due in part to archery's low cost as well as a desire for more simple and primitive hunting means.

However, standard arrows are only effective when used for shooting at fixed targets or hunting animals of moderate size because only a single projectile, the arrow itself, is capable of striking the target. Small game and birds, as well as the clay targets used in skeet and trap shooting, cannot effectively be used as targets of conventional arrows.

For this reason, there have been attempts to provide arrows capable of propelling a plurality of projectiles with a single arrow shot. Typical of these is U.S. Pat. No. 2,970,838 issued to Wilmer R. Taggart on Feb. 7, 1961. This patent discloses an arrow having a massive head holding a plurality of projectiles. After the arrow is fired, the projectiles are released, and the arrow is slowed aerodynamically to effect separation.

U.S. Pat. No. 3,021,139, issued to Henry P. Buerosse on Feb. 13, 1962, discloses an arrow head capable of projecting shot particles ahead of an arrow during flight. A spring is compressed during acceleration of the arrow on the bow and expands during flight separating the shot charge from the arrow by applying equal forces to each. The arrow is again decelerated primarily by aerodynamic drag.

Prior art shot arrows are incapable of transferring a significant amount of energy to the projectiles. Rather, much of the energy from the bow is retained by the massive arrow which therefore travels a significant distance down range making recovery difficult. More significantly, because of the limited transfer of energy from the arrow to the projectiles, largely due to the high mass and resultant low velocities of prior art arrows, and the large number of projectiles among which this energy is divided, the released projectiles may not have sufficient energy to kill small game or even break a clay target.

The shot propelling arrow of this invention overcomes these and other related limitations. The shot arrow of this invention generally comprises a tubular shaft sealed at its nocked end, the seal and a slideable piston retaining a compressible fluid therebetween. A plurality of shot particles are aligned along the longitudinal axis of the shaft and forwardly of the piston. Holding means may be used at an open forward end portion to retain shot particles in the shaft during positioning of the arrow on the bow, but not significantly slowing their velocity upon release.

When the arrow is released from a drawn bow, the shaft accelerates quickly while the shot only accelerates as the fluid pressure increases. The fluid is compressed by the inertial forces of the projectiles, until at an extreme high pressure the velocity of the shot reaches that of the arrow. The compressed fluid then acts equally on the arrow and the shot further accelerating the shot particles while decelerating the arrow. All of the energy of the arrow is subsequently transferred to the shot. Sufficient energy is thus imparted to

the shot particles to effectively kill small game while the arrow falls to the ground within a few feet of the bow.

It is an object of this invention to provide an arrow capable of effectively propelling a plurality of projectiles toward a target.

It is another object of this invention to provide an arrow capable of propelling a plurality of projectiles with sufficient energy for hunting small game or shooting skeet or trap targets.

It is still another object of this invention to provide a shot propelling arrow which falls to the ground in close proximity of the bow for easy retrieval after its projectiles have been released.

These and other objects and advantages of this invention will become apparent from the following specification when read in connection with the drawings wherein:

FIG. 1 illustrates an archer firing a shot propelling arrow of this invention from a bow;

FIG. 2 is a fragmentary sectional view of a shot propelling arrow of this invention;

FIG. 3 is a fragmentary sectional view of the shot propelling arrow of FIG. 2 wherein alternate embodiments of certain components of the arrow are shown;

FIG. 4 is a fragmentary sectional view of the shot propelling arrow of this invention showing additional embodiments of arrow components; and

FIG. 5 is a fragmentary sectional view illustrating adjusting means for the shot propelling arrow of this invention.

Referring now to FIG. 1, a shot arrow 11 is shown nocked on a bowstring 12 of a standard bow 14. It can be seen that the shot arrow 11 of this invention is fired from the bow 14 in substantially the same manner as a standard arrow.

The shot arrow 11 is best described with reference to FIG. 2 and has a tubular shaft 15 which has an open forward end portion 15a and a rear end portion 15b to which a nock 16 is attached by any suitable means. A seal 17, preferably molded of a suitable plastic, is mounted at the rear end portion 15b of the shaft 15 to prevent the passage of air therethrough and may have a forwardly extending obturating rim 17a. A compression chamber 18 is defined in the shaft 15 between the seal 17 and a piston 19 which is preferably molded of a suitable plastic such as high density polyethylene and is slidably mounted in the shaft 15. The piston 19 preferably has a rearwardly extending obturating rim 19a which enhances the air-sealing ability of the piston 19; the piston may also have a concave forward end portion 19b shaped to accommodate a shot particle 20 and a threaded opening 19c to facilitate adjustment of the piston 19 in a manner which will subsequently be further described. A plurality of metallic shot particles 20 are fitted into the shaft 15 forwardly of the piston 19. The shot particles 20 are preferably spherical steel projectiles having a diameter only slightly less than the inner diameter of the shaft 15 so that they form a single line of projectiles within the shaft. This arrangement prevents any jamming which might occur were significantly smaller particles used. The shot arrow 11 is preferably constructed to propel roughly 15 to 30 projectiles, the number depending upon the energy required per projectile. A modern bow can transfer about 20 ft. lb. to an arrow so if, for example, 1 ft. lb. per projectile were required, about 20 shot particles would be used.

Although fletching may be added to the shot arrow 11, it is not necessary or desired for proper operation of the shot arrow.

In the preferred embodiment, the shaft 15 preferably has an inner diameter of about 0.265 in. while the shot particles have a diameter of 0.250 in. If 20 shot particles are used, each preferably having a weight of about 1 gram, the weight of the shot propelling arrow is preferably about the same weight of the projectiles or about 20 grams.

Operation of the shot arrow of this invention will now be described. The shot arrow 11, loaded with a plurality of shot particles 20, is fired from a conventional bow 14 (FIG. 1) in a manner substantially the same as for the firing of a conventional arrow. The shot arrow 11 is nocked on the bowstring 12, and the bowstring is drawn back from its rest position to the full draw position illustrated in FIG. 1. When the bowstring 12 is released, the limbs of the bow 14, through the bowstring 12, exert a force accelerating the shot arrow 11 in a manner well known to those skilled in the art.

Referring now to FIG. 2, while the shaft 15 is being accelerated by the bowstring, the shot particles 20 and, accordingly, the piston 19 remain substantially fixed in position relative to the bow 14 due to inertia so that the seal 17 is effectively accelerated toward the piston 19. This action compresses the air which is trapped in the compression chamber 18 by the sealing action of the obturating rims 17a and 19a. As the speed of the shaft 15 increases, the pressure of this trapped air increases and applies a forwardly directed force to the piston 19 as shown by the arrow 24 in FIG. 2. This force causes forward acceleration of the piston 19 and shot 20, which acceleration is, however, at a much slower rate than that of the shaft.

As the seal 17 approaches the piston 19, the volume of the trapped air decreases further, thereby increasing its pressure. When the seal 17 very closely approaches the piston 19, the pressure increases at a much greater rate reaching an extremely high value, on the order of 10,000 psi, when the seal and piston come roughly within one-quarter inch of each other. This high pressure produces a corresponding high force on the piston 19, sufficient to overcome the inertia of the shot particles, thus accelerating the piston and shot particles 20 until the speed of the shot particles equals the speed of the shaft 15. This is the point of maximum pressure of the trapped air in the compression chamber 18.

The equal and opposite forces applied by the trapped air to the piston 19 and seal 17 now further accelerate the shot particles 20 and slow the shaft 15. If we assume the total mass of the shot particles 20 to be equal to the mass of the shot arrow 11 and neglect the effects of friction, the hereinabove described operation of the shot arrow 11 will cause the shot particles 20 to leave the shaft 15 and be propelled toward the target while the shaft 15 and piston 19, having transferred all forward kinetic energy to the shot, lose all forward velocity and fall to the ground.

Although the piston 19 is initially forwardly propelled with the shot particles 20, the pressure in the compression chamber 18 decreases below ambient as the piston moves forward of its initial position so that, before it can leave the shaft 15, the pressure in front of the piston is sufficiently higher than the pressure in the compression chamber to push the piston back toward its original position. Only a small pressure differential

is necessary because the piston is very light, and the tendency of the piston to leave the shaft is partially overcome by friction. It should be noted, however, that some leakage of air, either into or out of the compression chamber 18, may occur. Although this leakage would not be sufficient to allow the piston 19 to leave the shaft 15, it may cause the final position of the piston to be noticeably different from its position before the arrow 11 was fired. This may be corrected before a new load of shot particles 20 is loaded into the shaft 15 in a manner to be subsequently described herein with reference to FIG. 5.

The separation of the shot 20 from the shaft 15 physically appears as caused by an elastic "collision" between the shaft 15 and shot 20, the trapped air serving as a transfer medium whereby substantially all the energy applied to the shaft 15 by the bow 14 is transferred to the shot. If the shot arrow 11 is constructed so that the "collision" occurs at the moment the nock 16 leaves the bowstring 12, it can be seen that substantially all of the energy of the bow will be transferred to the arrow and used to propel the shot particles 20 to their target. Thus, by using the shot arrow of this invention, maximum transfer of the bow's energy to the shot can be effected while the arrow's shaft is made to fall near the archer's feet for easy retrieval.

It should be noted that certain factors can cause slight deviations from the optimum operating conditions hereinabove described. For example, frictional interaction between the inner surface of the shaft 15 and the piston 19 and shot particles 20 results in greater initial acceleration of the shot than would be produced by compression chamber pressure alone. This frictional interaction also prevents a complete transfer of energy so that some residual energy is retained by the shaft after the shot particles 20 have been expelled. However, it has been found that this only causes the shaft to travel a short distance (generally less than 10 ft.) before the shaft falls to the ground.

The adiabatic compression of the trapped air during the "collision" causes the temperature of the air to increase greatly. Were a small quantity of oil, or some other combustible material, inadvertently introduced in the shaft and subjected to this temperature, this high compressive temperature could result in a small explosion which, while insufficient to damage the arrow, could tend to propel the shaft 15 rearwardly after the impact. Therefore, it is advantageous to construct the shot arrow 11 so that the "collision" and maximum air temperature occur shortly before the nock 16 leaves the bowstring 12.

This may be accomplished by elongating the rear seal so that it is constructed substantially in the form illustrated as seal 117 of FIG. 3. It should be readily apparent that since the point of "collision" between the piston and rear seal occurs when their velocities become equal, the point of "collision" is dependent upon the pressure buildup in the compression chamber 18 and thus related to the length of the chamber. Accordingly, if the forward end portion of the seal 117 is extended forwardly to decrease the length of the compression chamber 18, the pressure increase, and accordingly the acceleration of the piston 19, will occur at a greater rate so that the "collision" will occur at an earlier point in the flight of the shot arrow 11. By controlling the length of the seal 117, the point of "collision" can be controlled so that it occurs at any desired point. In this

manner, the occurrence of the "collision" before the nock leaves the bowstring 12 can be assured so that, should "diesel" ignition of any combustibles in the shaft 15 occur, the resultant explosion will only serve to increase the energy imparted to the shot particles 20 and not likely present a hazard to the archer.

Further, it is well known that a recurve bow applies an additional force to an arrow just before the arrow leaves the string. If the "collision" and this last "kick" by the bow occur at about the same time, the effective mass of the arrow being accelerated by the bow will be increased to optimize the efficiency of the transfer of energy to the arrow during application of the recurve force, as will be readily apparent to those skilled in the art.

Another embodiment of the seal is illustrated in FIG. 4 and designated as seal 217. The point of "collision" of the arrow 11 can be controlled through the use of the seal 217 without any adjustment of the length of the seal. Only its position need be altered. When the seal 217 is secured in place by a suitable epoxy-type adhesive, the forward and rear obturating rims 217a and 217b, respectively, maintain the integrity of the air seals so that the seal 217 performs a function substantially identical to the seal 117. It should be noted that due to the size of the seal 117 of FIG. 3, its use significantly increases the mass of the shot arrow 11 while no such increase is produced by use of the seal 217. Clearly, the embodiment of the seal described would depend upon the mass which must be added to the shaft 15 to match the weight of the shot propelling arrow 11 to that of the shot 20 for optimum performance of the shot arrow as previously described. For example, if 25-30 projectiles were to be fired, a more massive arrow would preferably be used and, accordingly, a heavier sealing means such as the seal 117 of FIG. 3 is desirable. If 15 projectiles are fired, a lighter arrow and, possibly, the seal 217 would be required. Additionally, other sealing means may be used without departing from the spirit and scope of this invention.

As previously indicated, when the shot arrow 11 is fired, some air may leak past the piston 19, either into or out of the compression chamber 18, so that the final position of the piston 19 is altered. To preserve the operating characteristics of the arrow, it is thus necessary to move the piston 19 to its former rest position so that the compression chamber 18 will be of proper length. For this purpose, an adjusting means such as an adjusting rod 21 shown in FIG. 5 may be used. The adjusting rod 21 may be of any desired length sufficient to extend through the open forward end portion 15a of the shaft 15 and has a threaded end portion 21a for attachment to the threaded opening 19c of the piston 19.

It should be readily apparent that after attachment of the adjusting rod 21 to the piston 19, the rod may be moved slowly to relocate the piston. This slow motion of the piston 19 will permit air to flow around it as will be readily understood by those skilled in the art.

The final location of the piston 19 may be accurately determined by the use of calibration marks 21b, one or more of which would be preferably positioned on the adjusting rod 21. Alignment of a suitable calibration mark 21b with the forward end portion 15a of the shaft 15 would show that the piston 19 was properly positioned.

It is desired to retain the shot particles 20 in the shaft 15 for an extended time period prior to shooting

the shot arrow 11 or if there is a possibility that the shot may fall out of the shaft 15 before or during firing, a suitable shot retaining means should be used.

FIG. 3 illustrates a retainer 22 which may be molded of rubber or other suitable material and is shaped to have an inwardly directed circumferential lip 22a. The retainer 22 is fitted onto the shaft 15 with the circumferential lip 22a positioned against, and extending inwardly of, the forward end portion 15a of the shaft. The circumferential lip 22a should be dimensioned to loosely hold the most forwardly positioned shot particle 20 within the shaft 15 while the shot arrow 11 is at rest but to readily release the shot particles 20 with a minimum loss of energy of the particles when the arrow is fired. The retainer 22 serves the additional function of protecting the forward end portion 15a of the shaft 15 against damage when the shot arrow 11 falls to the ground and helping to prevent dirt, grass or other debris from entering the shaft 15. If desired, the lip 22a may be segmented or cover only a portion of the periphery of the opening so that energy loss is minimized. The lip 22a need only hold the shot particles 20 against being inadvertently allowed to fall from the open forward end portion 15a of the shaft 15.

FIG. 4 illustrates an alternate shot retaining means in the form of a knock-off closure 24 which is preferably fitted over the forward end portion 15a of the shaft and is detached therefrom by the most forwardly directed shot particle 20 when the arrow is fired.

In this manner, a shot propelling arrow is disclosed which effectively propels a plurality of shot particles toward a target transferring substantially all of the energy imparted by the bow thereto, the shot arrow falling to the ground within a few feet of the bow.

It should be understood that components of the shot arrow 11 may be further modified if desired. For example, a rear seal may be used wherein two generally frusto-conical members are threaded together to expand a tubular plastic sleeve into tightly fitting, sealing relationship within the shaft 15. Such a rear seal would function in a manner similar to the rear seal 217 of FIG. 4 and, additionally, could be moved within the shaft for removal or repositioning by loosening the threaded members. Although the shot arrow 11 has been described in conjunction with discrete, spherical steel shot particles 20, it should be understood that other projectiles, including elongated projectiles, shot particles which are connected in one or more long chains, or projectiles having a cylindrical or other desired shape may be used without departing from the spirit and scope of this invention. The shot particles 20 may be formed of any desired material having sufficient hardness to withstand the large magnitude forces produced when the shot propelling arrow 11 is fired without significant deformation which would detract from the effectiveness of the arrow.

We claim:

1. An arrow for propelling a plurality of projectiles, said arrow comprising a tubular shaft having an open forward end portion, a rear end portion and a generally uniform cross section, piston means mounted in slideable sealing relation in the shaft and defining a projectile holding portion in the shaft forwardly of the piston means, means sealing the shaft rearwardly of the piston means, and compressible fluid in the shaft between the piston means and the sealing means, the piston means including a forwardly directed threaded opening en-

gageable by an adjusting rod having a threaded end portion for controlling the length of compressible fluid between the piston means and the sealing means.

2. An arrow as in claim 1 wherein nock means is attached at the rear end portion of said shaft for engaging a bowstring. 5

3. An arrow as in claim 1 wherein a calibration mark is provided at a predetermined location on said adjusting rod.

4. An arrow for propelling a plurality of projectiles, said arrow comprising a tubular shaft having an open forward end portion, a rear end portion and a generally uniform cross section, piston means mounted in slideable sealing relation in the shaft, a plurality of linearly aligned projectiles positioned in the shaft forwardly of the piston means, a rear seal mounted in the shaft rearwardly of the piston means, and compressible fluid in the shaft between the piston means and the sealing means, the weight of the plurality of projectiles being substantially equal to the total weight of the tubular shaft, piston means and rear seal. 10

5. An arrow as in claim 4 wherein said rear seal has a forward end portion, said piston means and the forward end portion of said sealing means define a compression chamber in said shaft, and the forward end portion of said rear seal is positioned to provide a predetermined length for the compression chamber. 25

6. An arrow as in claim 4 including projectile retaining means mounted at the forward end portion of said shaft. 20

7. An arrow as in claim 6 wherein said projectile retaining means comprises a knock-off closure. 25

8. An arrow as in claim 6 wherein said projectile retaining means comprises inwardly directed lip means

blocking a portion of the open forward end portion of said shaft.

9. An arrow as in claim 8 wherein said lip means is a continuous peripheral lip. 5

10. An arrow as in claim 4 wherein said compressible fluid is air. 15

11. A projectile propelling bow and arrow system comprising a bow including a bowstring and an arrow, separable from the bow upon release of the bowstring, the arrow comprising a tubular shaft having an open forward end portion and a nocked rear end portion for engaging the bowstring, piston means mounted in slideable sealing relation in the shaft, sealing means mounted in the shaft, compressible fluid in the shaft between the piston means and the sealing means, and a plurality of projectiles positioned in the shaft forwardly of the piston means, the distance between the piston means and the sealing means permitting maximum compression of the compressible fluid just prior to separation of the arrow from the bowstring upon release of the bowstring. 20

12. A projectile propelling bow and arrow system as in claim 11 wherein said projectiles are metallic and generally spherical in shape. 25

13. A projectile propelling bow and arrow system as in claim 11 wherein said compressible fluid is air. 30

14. A projectile propelling bow and arrow system as in claim 11 wherein said projectiles are disposed in a line axially aligned in said shaft. 35

15. A projectile propelling bow and arrow system as in claim 11 wherein the weight of said plurality of projectiles is substantially equal to the total weight of said tubular shaft, said piston means and said sealing means.
